(57) **CLAIM**

The ornamental design for a receptacle for modular wiring systems, as shown and described.

DESCRIPTION

FIG. 1 is a front perspective view of a receptacle for modular wiring systems showing our new design;

FIG. 2 is another front perspective view taken from an opposite end thereof;

FIG. 3 is a front elevation thereof;

FIG. 4 is a left side elevation thereof;

FIG. 5 is a right side elevation thereof;

FIG. 6 is a bottom plan view thereof;

FIG. 7 is a top plan view thereof;

FIG. 8 is a front perspective view of another receptacle for modular wiring systems showing our new design;

FIG. 9 is another front perspective view taken from an opposite end thereof;

FIG. 10 is a front elevation thereof;

FIG. 11 is a left side elevation thereof;

FIG. 12 is a right side elevation thereof;

FIG. 13 is a bottom plan view thereof;

FIG. 14 is a top plan view thereof;

FIG. 15 is a front perspective view of another receptacle for modular wiring systems showing our new design;

FIG. 16 is another front perspective view taken from an opposite end thereof;

FIG. 17 is a front elevation thereof;

FIG. 18 is a left side elevation thereof;

FIG. 19 is a right elevation thereof;

FIG. 20 is a bottom plan view thereof; and,

FIG. 21 is a top plan view thereof.

In the drawings, the broken lines depict unclaimed subject matter only and form no part of the claimed design.

1 Claim, 6 Drawing Sheets
